CLOCK SPRING ANCHORING MEANS

Ferdinand Fengler, Bristol, Conn., assignor to
 The E. Ingraham Company, Bristol, Conn., a
 corporation of Connecticut

Application May 7, 1946, Serial No. 667,931

3 Claims. (Cl. 58—52)

1

The present invention relates in general to timepieces and more especially to improved means for securing the main and alarm springs of a timepiece to the frame.

Heretofore, the free or outer ends of the main-springs and alarm springs of timepieces have been made fast to the frames by fastening-means comprising, almost universally, a separate clamp or a clamp formed integrally on the outer end of the spring and secured to one of the pillars of the frame by a rivet or similar type of fastening-means. This construction is not only relatively expensive but necessitates that the entire frame be disassembled to replace a broken spring.

An object of the invention is to provide improved means for anchoring the outer or free ends of the main and alarm springs of a timepiece to the frame.

A further object is to provide improved main-spring fastening-means to enable the spring to be engaged with and disengaged from the frame of the timepiece without disassembling the frame.

A still further object is to provide an aperture in the outer end of a timepiece spring adapted to engage over a projection on the frame to anchor the spring to the frame.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a fragmentary plan view of the frame of a timepiece embodying the improved spring-anchoring means of this invention;

Fig. 2 is a front elevation of the frame showing the spring-anchoring means in Fig. 1;

Fig. 3 is a sectional view on line 3—3 of Fig. 1; and

Fig. 4 is a modification.

Referring to the drawings which illustrate an exemplary embodiment of the invention, the timepiece-frame is indicated generally at 10 and comprises front and rear movement-plates 11 and 12 held in spaced parallel relationship by pillars 13. Mounted between the front and rear movement-plates are gear-trains comprising a time-train indicated generally at 14 and an alarm-train 15. The time-train 14 is of conventional construction and is driven by the force of a wound spiral mainspring such as shown at 16, the latter being supported on a winding-arbor 17 which is

2

rotatably mounted at its opposite ends in the front and rear movement-plates. The rear extremity of the winding-arbor 17 is provided with the usual winding-key 18 for manually rotating the arbor 17. The mainspring 16 is secured at its inner end 19 to the winding-arbor 17, the connection between the inner end of the spring and the arbor being the usual type of fastening-means 20, as shown in Fig. 3.

The opposite or outer end 21 of the mainspring 16 is adapted to be anchored to the frame 10 in a manner such as to enable the outer end 21 of the spring to be readily attached thereto and removed therefrom with dispatch and without necessitating the disassembly of the entire frame. To this end, the outer extremity 21 of the mainspring 16 is reduced in width as shown in Fig. 3, the reduced portion constituting a tongue 22 having a radius at its outer end and a longitudinal slot 23. The slot 23 is substantially rectangular, its longitudinal axis being coincident with the longitudinal axis of the tongue 22.

The frame 10 of the timepiece is provided with a projection 24 which is an integral extension of the rear movement-plate 12. The projection comprises an enlarged head-portion 26 connected to the rear movement-plate 12 by a reduced neck-portion 27, the inner and outer edges of which constitute two substantially V-shaped notches 28 and 29 the outwardly-diverging walls of each notch forming shoulders 30 and 31, respectively. The width and length of the slot 23 in the outer extremity of the mainspring correspond substantially to the thickness and width respectively of the head-portion 26 of the frame-projection 24, as a consequence of which the slotted end of the spring is adapted to be slipped over the head-portion 26 and to engage against the inner shoulders 30 and 31 of the respective notches 28 and 29. Since the length of the slot 23 is greater than the width of the neck-portion 27 of the projection 24, the force of the wound mainspring 16, which normally tends to move the outer free end 21 thereof in a direction to unwind the mainspring, acts to pull the free end of the spring inwardly, as seen in Fig. 1 whereby the outer end of the slot 23 is shifted into the bottom of the outer notch 28, as shown in Fig. 3. The outer end of the spring is thus engaged between the outwardly-diverging shoulders 30 of the notch 28, thus effectively anchoring the slotted-end of the spring to the frame without requiring the use of rivets, sleeves or any other additional securing means. The slotted-end of the spring may be readily slipped off of the projection 24 without separat-

ing the front and rear movement-plates 11 and 12 respectively of the frame, simply by pulling the free end of the spring in a direction counter to its normal bias so as to move the outer end of the slot 23 over the left-hand shoulder 30 of the outer notch 28, as seen in Fig. 1.

A further application of the slotted-spring structure is illustrated in Fig. 4 wherein the projection 24a of the rear movement-plate 12a comprises a tongue-shaped extension having substantially-parallel inner and outer edges 28a and 29a respectively, and a circular outer end 32a. A shoulder 31a is formed at the junction of the inside edge 29a of the extension with the rear-plate 12a of the frame. The width of the slot 23a in the free end of the spring 22a is substantially equal to the width of the tongue-element 24a, as a consequence of which the free end of the spring may be slipped over the tongue 24a and moved up into engagement with the shoulder 31a. Normally, the force of the wound or partially-wound mainspring acting to pull the free end of the spring in a counterclockwise direction, as seen in Fig. 4, binds the slotted free end of the spring on the tongue 24a so as to effectively anchor the free end of the spring thereto. As a precaution against any possibility of the free end of the spring slipping off of the tongue-shaped extension 24a, the pillar 13a at this corner of the frame of the timepiece is supported in an aperture in the outer end of the extension 24a so that the nut 33 and spacing-collar 34 on the upper end of the pillar, are located adjacent the outside face of the free end of the spring and thus positively prevent accidental removal of the free end of the spring from the extension 24a.

Although the description relates in particular to the mainspring fastening-means of a timepiece, it will be understood that a similar type of fastening-means is applicable to the alarm spring of timepieces embodying an alarm-train.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a timepiece having a frame comprising front and rear movement-plates, a gear-train, a spring for driving said gear-train, said spring having a substantially-rectangular slot in its outer end, a spring-winding arbor and means to secure the inner end of said spring to said arbor; of a projection on the said rear movement-plate the cross-sectional dimensions of said projection being substantially equal to the dimensions of said rectangular slot to permit said projection to make a snug fit in said aperture so as to secure the said outer end of said spring to said frame; and a pillar supported in the outer end of said projection adjacent the outer face of the free end of said spring to positively keep the free end of said spring on said projection.

2. In a timepiece, the combination including: a frame having spaced parallel front and rear movement-plates; a gear-train; a spring driving said gear-train, said spring being formed with

5 a reduced tongue-portion at its outer end having a substantially-rectangular slot therein extending longitudinally thereof; a spring-winding arbor arranged to support said spring between said front and rear movement-plates in spaced substantially-parallel relationship thereto; means to secure the inner end of said spring to said arbor; a projection on one of said movement-plates, the plane intersecting the opposite edges of said projection coinciding with the plane of the said one movement-plate, the plane of said projection being also substantially perpendicular to a plane intersecting the opposite edges of said tongue, the width of said projection being substantially equal to the length of said rectangular slot so as to engage therein with a substantially-close fit with the end of said projection extending outwardly beyond the slotted tongue of said spring; and means on the outwardly-extending end of said projection immediately adjacent the outer face of said slotted tongue to positively retain the slotted end of said tongue on said projection.

3. In a timepiece, the combination including: a frame having spaced parallel front and rear movement-plates; a gear-train; a spring for driving said gear-train, said spring being formed with a reduced tongue-portion at its outer end having a substantially-rectangular slot therein extending longitudinally thereof; a spring-winding arbor arranged to support said spring between said front and rear movement-plates in spaced substantially-parallel relationship thereto; means to secure the inner end of said spring to said arbor; a projection on one of the said movement-plates, the plane intersecting the opposite edges of said projection coinciding with the plane of the said one movement-plate, the said plane of said projection being also substantially perpendicular to a plane intersecting the opposite edges of said tongue, said projection comprising an enlarged head-portion joined integrally to the edge of the said one movement-plate by a reduced neck-portion symmetrical with respect to said head-portion and forming spring-retaining shoulders therewith and with the corresponding edge of the said one movement-plate, the cross-sectional dimensions of said head-portion being substantially equal to the corresponding dimensions of said rectangular slot to permit the slotted tongue of said spring to be slipped over said enlarged head-portion into engagement with the said reduced neck-portion of said projection, the said spring-retaining shoulders thereof being arranged to positively retain said slotted tongue on said reduced neck-portion.
